(57) **ABSTRACT**

A downlight includes a cover, a reflector cup, a light source, a housing, and two springs. The housing has a boss, and an opening surface of the boss extends radially outward to form a skirt. The cover is disposed on the opening surface of the boss to be spliced to the housing to form a cavity for accommodating the reflector cup and the light source, and the reflector cup is disposed on a light-emitting surface of the light source to enable light emitted by the light source to be reflected to be emitted out of the cover. The housing comprises two slots. The two springs are configured to be respectively detachably connected to the two slots, and a selective one of two sub-slots of each of the two slots receives a corresponding one of the two springs.

FIG.4

1
DOWNLIGHT

RELATED APPLICATIONS

This application claims priority to Chinese patent application number 202322895235.9, filed on Oct. 27, 2023. Chinese patent application number 202322895235.9 is incorporated herein by reference.

FIELD OF THE DISCLOSURE

The present disclosure relates to a lighting device, and in particular to a downlight.

BACKGROUND OF THE DISCLOSURE

Springs of traditional downlights are secured by screws, which is troublesome in production. Additionally, the springs stand upright, increasing a size of a packaging box and significantly adding to cost.

BRIEF SUMMARY OF THE DISCLOSURE

The technical problem to be solved by the present disclosure is to provide a downlight that reduces the costs of assembling and packaging springs.

In order to solve the above technical problems, the present disclosure provides a downlight comprising a cover, a reflector cup, a light source, a housing, and two springs. The housing has a boss extending along a thickness direction of the housing, and an opening surface of the boss extends radially outward to form a skirt. The cover is disposed on the opening surface of the boss to be spliced to the housing to form a cavity for accommodating the reflector cup and the light source, and the reflector cup is disposed on a light-emitting surface of the light source to enable light emitted by the light source to be reflected to be emitted out of the cover. The housing comprises two slots symmetrically located on an outer side of the boss, and each of the two slots is divided in two sub-slots. The two springs are configured to be respectively detachably connected to the two slots, and a selective one of the two sub-slots of each of the two slots receives a corresponding one of the two springs.

In a preferred embodiment, each of the two sub-slots comprises two side walls spaced apart from each other in a thickness direction of the two sub-slots, and a side wall of the two side walls away from the boss comprises a buckling block configured to be buckled to the corresponding one of the two springs. The buckling block is defined on a rib, and a first end of the rib is a fixed end and a second end of the rib is a free end, so that the rib is configured to be driven by an external force to enable the buckling block to swing in a direction of releasing a buckling connection with the corresponding one of the two springs.

In a preferred embodiment, the buckling block comprises an inclined surface. When the corresponding one of the two springs is inserted into a corresponding one of the two slots, a force generated by the two springs pressing the inclined surface causes the rib and the buckling block to swing in the direction of releasing the buckling connection with the corresponding one of the two springs.

In a preferred embodiment, each of the two springs comprises two supporting arms and an insertion portion for insertion into the two slots, and the two supporting arms extend in opposite directions.

In a preferred embodiment, the insertion portion is connected to the two supporting arms by a transition portion

2

extending in a horizontal direction, and the two springs are configured to be inserted into the two slots in different directions so as to enable the transition portions of the two springs to extend to face each other or face away from each other to adjust a distance between two sets of the two supporting arms of the two springs.

In a preferred embodiment, the downlight comprises a toggle switch for changing color temperature, and the toggle switch is disposed on a back of the boss and is connected to a driver circuit board on the light source.

In a preferred embodiment, the downlight comprises a toggle switch for changing color temperature, and the toggle switch is disposed on a side of the skirt facing a light-emitting direction and is connected to the driver circuit board on the light source.

In a preferred embodiment, upper and lower end surfaces of the two sub-slots are at different heights, so that when the two springs are inserted into different sub-slots of the two sub-slots, a height at which the two springs are positioned is different.

Compared with the existing techniques, the technical solution has the following advantages.

The present disclosure provides the downlight that allows the two springs to be buckled to the housing when installing the downlight. This reduces production costs. Additionally, a reduced height of the downlight directly decreases packaging costs. Moreover, due to the presence of multiple slots, the two springs can be buckled to the two slots in different directions to adjust a distance between the two springs to enable the downlight to be mounted on holes of different diameters. Alternatively, the height at which the two springs are positioned can be adjusted to enable the downlight to be mounted on holes of different depths. This makes installation very convenient.

BRIEF DESCRIPTION OF THE DRAWINGS

FIG. 1 is an exploded view of a preferred embodiment of the present disclosure.

FIG. 2 is a front view of the present disclosure.

FIG. 3 is a rear view of the present disclosure.

FIG. 4 is a schematic diagram of two springs and buckling blocks of the present disclosure.

DETAILED DESCRIPTION OF THE EMBODIMENTS

The following will clearly and completely describe the technical solutions in the embodiments of the present disclosure with reference to the accompanying drawings. Obviously, the described embodiments are only a portion of the embodiments of the present disclosure, and not all of the embodiments. Based on the embodiments of the present disclosure, all other embodiments obtained by those of ordinary skill in the art without creative work fall within the protection scope of the present disclosure.

In the description of the present disclosure, it should be noted that the terms "upper", "lower", "inner", "outer", "top end", "bottom end", etc. indicate the orientation or positional relationship based on the orientation shown in the drawings. The positional relationship is only for the convenience of describing the present disclosure and simplifying the description, rather than indicating or implying that the referenced device or element must have a specific orientation, be constructed, and be operated in a specific orientation. Therefore, the positional relationship should not be understood as a limitation of the present disclosure. In

addition, the terms "first" and "second" are only used for descriptive purposes and should not be understood as indicating or implying relative importance.

In the description of the present disclosure, it should be noted that the terms "installed", "provided with", "sleeved/connected", "connected", etc., should be understood broadly. For example, "connected" can be a wall hanging connection, a detachable connection, or an integral connection, a mechanical connection, an electrical connection, a direct connection, or an indirect connection through an intermediate medium, and it can be a connection between two members. For those of ordinary skill in the art, the specific meaning of the above terms in the present disclosure can be understood under specific conditions.

Referring to FIGS. 1 to 4, this embodiment discloses a downlight with multiple installation methods, comprising: a cover 1, a reflector cup 2, a light source 3, a housing 4, and two springs 5.

The housing 4 has a boss 41 extending along a thickness direction of the housing 4, and an opening surface of the boss 41 (i.e., a surface of the boss 41 defining an opening) extends radially outward to form a skirt 43. The cover 1 is disposed on the opening surface of the boss 41 to be spliced to the housing 4 to form a cavity for accommodating the reflector cup 2 and the light source 3. The reflector cup 2 is disposed on a light-emitting surface of the light source 3 to enable light emitted by the light source 3 to be reflected to emit out through the cover 1.

The housing 4 comprises two slots symmetrically located on an outer side of the boss 41, and each of the two slots can be divided in two sub-slots 42. The two springs 5 are configured to be respectively detachably connected to the two slots, and a selective one of the two sub-slots 42 of each of the two slots receives a corresponding one of the two springs 5.

To form the aforementioned detachable fit, each of the two sub-slots 42 comprises two side walls spaced apart from each other in a thickness direction of the two sub-slots 42, and a side wall of the two side walls away from the boss 41 comprises a buckling block 421 configured to be buckled to the corresponding one of the two springs 5. The buckling block 421 is defined on a rib 422 (e.g., a cantilever on the side wall of the two side walls). A first end of the rib 422 is a fixed end, and a second end of the rib 422 is a free end, so that the rib 422 can be driven by an external force to enable the buckling block 421 to swing in a direction of releasing a buckling connection with the corresponding one of the two springs 5. Therefore, the external force can act on the rib 422 to release an interlocking connection between the buckling block 421 and the corresponding one of the two springs 5, and the corresponding one of the two springs 5 can be taken out of the two sub-slots 42.

The above structure enables a separation of the buckling block 421 and the corresponding one of the two springs 5. To allow the corresponding one of the two springs 5 to be inserted into the selective one of the two sub-slots 42 and to be buckled to the buckling block 421 of the selective one of the two sub-slots 42, the buckling block 421 comprises an inclined surface. When the corresponding one of the two springs 5 is inserted into the selective one of the two sub-slots 42, a force generated by the selective one of the two sub-slots 42 pressing the inclined surface causes the rib 422 and the buckling block 421 to swing in the direction of releasing the buckling connection with the corresponding one of the two springs 5.

In this embodiment, each of the two springs 5 comprises two supporting arms 51 and an insertion portion 52 for

insertion into the two sub-slots 42. The two supporting arms 51 extend in opposite directions. The insertion portion 52 is connected to the two supporting arms 51 by a transition portion 53 extending in a horizontal direction. The two springs 5 are inserted into the two slots in different directions so as to allow the transition portions 53 of the two springs 5 to extend to face each other or face away from each other to adjust a distance between two sets of the two supporting arms 51 of the two springs 5.

Upper and lower end surfaces of the two sub-slots 42 are at different heights, so that when the two springs 5 are inserted into different sub-slots 42 of the two sub-slots 42, a height at which the two springs 5 are positioned is different.

The aforementioned downlight allows the two springs 5 to be buckled to the housing 4 only when installing the downlight. This reduces production costs. Additionally, a reduced height of the downlight directly decreases packaging costs. Moreover, due to the presence of multiple slots, the two springs 5 can be buckled to the two slots in different directions to adjust a distance between the two springs 5 to enable the downlight to be mounted on holes of different diameters. Or, the height at which the two springs 5 are positioned can be adjusted to enable the downlight to be mounted on holes of different depths. This makes installation very convenient.

This embodiment also includes a toggle switch 6 for changing color temperature. The toggle switch 6 is disposed on a back of the boss 41 and is connected to a driver circuit board 31 on the light source 3. As a simple alternative, the toggle switch 6 is disposed on a side of the skirt 43 facing a light-emitting direction and is connected to the driver circuit board 31 on the light source 3.

The aforementioned embodiments are merely some embodiments of the present disclosure, and the scope of the disclosure is not limited thereto. Thus, it is intended that the present disclosure cover any modifications and variations of the presently presented embodiments provided they are made without departing from the appended claims and the specification of the present disclosure.

What is claimed is:

1. A downlight, comprising:
a cover,
a reflector cup,
a light source,
a housing, and
two springs, wherein:

the housing has a boss extending along a thickness direction of the housing, an opening surface of the boss extends radially outward to form a skirt, the cover is disposed on the opening surface of the boss to be spliced to the housing to form a cavity for accommodating the reflector cup and the light source, the reflector cup is disposed on a light-emitting surface of the light source to enable light emitted by the light source to be reflected to be emitted out of the cover, the housing comprises two slots symmetrically located on an outer side of the boss, each of the two slots is divided in two sub-slots, the two springs are configured to be respectively detachably connected to the two slots, and a selective one of the two sub-slots of each of the two slots receives a corresponding one of the two springs.

5

2. The downlight according to claim 1, wherein:
each of the two sub-slots comprises two side walls spaced
apart from each other in a thickness direction of the two
sub-slots,
a side wall of the two side walls away from the boss 5
comprises a buckling block configured to be buckled to
the corresponding one of the two springs,
the buckling block is defined on a rib, and
a first end of the rib is a fixed end and a second end of the
rib is a free end, so that the rib is configured to be
driven by an external force to enable the buckling block
to swing in a direction of releasing a buckling connec-
tion with the corresponding one of the two springs.
3. The downlight according to claim 2, wherein:
the buckling block comprises an inclined surface, and
when the corresponding one of the two springs is inserted
into a corresponding one of the two slots, a force
generated by the two springs pressing the inclined
surface causes the rib and the buckling block to swing
in the direction of releasing the buckling connection
with the corresponding one of the two springs.
4. The downlight according to claim 2, wherein:
each of the two springs comprises two supporting arms
and an insertion portion for insertion into the two slots, 15
and
the two supporting arms extend in opposite directions.
25

6

5. The downlight according to claim 4, wherein:
the insertion portion is connected to the two supporting
arms by a transition portion extending in a horizontal
direction, and
the two springs are configured to be inserted into the two
slots in different directions so as to enable the transition
portions of the two springs to extend to face each other
or face away from each other to adjust a distance
between two sets of the two supporting arms of the two
springs.
6. The downlight according to claim 1, wherein:
the downlight comprises a toggle switch for changing
color temperature, and
the toggle switch is disposed on a back of the boss and is
connected to a driver circuit board on the light source.
7. The downlight according to claim 1, wherein:
the downlight comprises a toggle switch for changing
color temperature, and
the toggle switch is disposed on a side of the skirt facing
a light-emitting direction and is connected to the driver
circuit board on the light source.
8. The downlight according to claim 1, wherein:
upper and lower end surfaces of the two sub-slots are at
different heights, so that when the two springs are
inserted into different sub-slots of the two sub-slots, a
height at which the two springs are positioned is
different.
